(57) **CLAIM**

The ornamental design for the cooler, as shown.

DESCRIPTION

FIG. 1 is an upper perspective view showing our new design for a cooler including a lid attached thereto.

FIG. 2 is a left side plan view thereof including the lid attached thereto.

FIG. 3 is a right side plan view thereof including the lid attached thereto.

FIG. 4 is a top side plan view thereof including the lid attached thereto.

FIG. 5 is a bottom side plan view thereof.

FIG. 6 is a front side plan view thereof including the lid attached thereto.

FIG. 7 is a back side plan view thereof including the lid attached thereto.

FIG. 8 is an upper perspective view thereof showing the lid removed therefrom; and,

FIG. 9 is a top side plan view thereof showing the lid removed therefrom.

The broken lines are for illustrative purposes only and form no part of the claimed design.
